UNITED STATES PATENT OFFICE.

HERMAN ROTHKIRCH, OF NEW YORK, N. Y.

PHONOGRAPH.

Application filed April 7, 1921. Serial No. 459,300.

To all whom it may concern:

Be it known that I, HERMAN ROTHKIRCH, a citizen of the United States, and resident of the borough and county of Queens, city 5 and State of New York, have invented certain new and useful Improvements in Phonographs, of which the following is a specification.

My invention relates to phonographs and 10 has for its object to provide an instrument of this character which is of maximum efficiency in the reproduction of the records being played and in which all objectionable and foreign noises are eliminated from said 15 reproduction. Other more specific objects of my invention will appear from the description hereinafter and the features of novelty will be pointed out in the appended claims.

20 Reference is to be had to the accompanying drawings which illustrate an example of my invention without defining its limits and in which Figure 1 is a plan view of my improved phonograph; Fig. 2 is a sectional elevation thereof; Fig. 3 is a horizontal section on the line 3—3 of Fig. 2; Fig. 4 is a front elevation; Figs. 5 and 6 are detail views of the tone arm; and Fig. 7 is a view illustrating a detail of the invention.

25 As shown in the drawings, the phonograph comprises a casing 10 of suitable conformation and which, as shown, may be constructed to simulate a grand piano and in any event diverges toward its front or outlet 30 end and constitutes in itself a part of the sound conduit of the phonograph. When constructed as illustrated in the example shown, the casing 10 may be mounted upon legs or other supports 11 and may be provided 35 with a closure whereby the exit end is capable of being closed. As shown, the closure may comprise a cover 12 and a carrying member 13 shaped to correspond to the customary key-board cover of the piano, the carrying member being preferably constructed 40 to provide an opening 14 for the escape of the sound when the cover 12 is closed. In the preferred arrangement, the closure is completely removable and is held 45 in place, for instance, by means of blocks 15 carried by the member 13 and arranged to be clamped beneath lugs 16 located upon the casing 10, by means of resilient locking members 17 also located on said casing 10.

50 With the arrangement described and assuming the closure to be in place, the cover 12 may occupy either the closed position shown 55 in full lines in Fig. 2, in which case the muffled sound escapes through the opening 14, or the open position shown by dotted line in said figure or said closure may be completely removed by simply overcoming the 60 resistance of the fastening devices 17 to completely open the outlet end of the casing 10, in either of which cases the escaping sound 65 is of increased loudness.

The top of the casing 10 consists of a fixed member 18 of relatively light construction and a removable cover 19 of relatively heavier construction and insulated from the 70 casing 10 and fixed member 18, for instance by means of leather or similar material 19^a as shown in Fig. 2, said cover 19 being detachably secured in place in any suitable manner as, for instance by means of screws 75 20, the heads of which are preferably insulated with leather or similar covers 21, and the shanks of which extend loosely through holes 19^b, as shown in Fig. 7, for the purpose to be more fully described hereinafter. 80 The customary motor 22, which may be of any existing type, is suspended from the cover 19 by means of screws 22^a and has its driving arbor 23 projecting upwardly through an opening 24 in said cover 19. The 85 arbor 23 is arranged to removably receive the rotating table 25 in the well known way, said table being adapted, as usual, to form a support for the record 26 to be played. A lever 27 for controlling the starting and 90 stopping of the motor is located in a readily accessible position and a speed-changing device 28 of any well known type may also be included in the arrangement. The bottom 29 of the casing 10 is constructed so as to be extremely responsive to vibration and is made 95 of relatively thin material, preferably wood, and at its forward edge may be provided with a reinforcing strip 30; in the preferred arrangement, said bottom 29 is curved inwardly both longitudinally, as indicated in Fig. 2, and transversely, as indicated by dotted lines in Fig. 4. This result is attained by bending the wood and thereby placing at 100 least some of the fibres thereof under a tension which serves to increase the resonance of the bottom to a maximum degree. The tone arm 31, which constitutes a part of the sound conduit, is preferably of rectangular cross-section and in its preferred embodiment 110 is constructed entirely of wood in a curved form, as shown in Fig. 2, and at its forward

2

end communicates with and carries the reproducer 32 which may be of any existing type. In its illustrated form, the upper and lower walls of the sound conduit or, more specifically, the tone arm 31 are bent into curved form whereby at least some of the fibres of the wood are placed under tension and the resonance of the tone arm as a whole is also increased to a maximum degree. It will be understood that this method of increasing the resonance of the bottom 29 and tone arm 31 may be applied with equal success to sound conduits of other and different construction than that shown in the drawings. The tone arm 31, in the illustrated example, extends through a suitable opening 33 in the top member 18 and is provided with a pivot member 34 which is seated in a socket 35 formed in a coupling head 36; the latter is mounted upon a resilient member 37 preferably constructed of wood and having its one end secured to a bridge or block 38 which in turn is fastened to the bottom 29 at approximately its central point, as shown in Fig. 2. With this arrangement the tone arm is resiliently supported upon the bottom of the casing in a manner to yield vertically and so as to be movable across the record in a horizontal plane in the usual way. For the purpose of avoiding the use of metallic fastening devices as far as possible and thereby doing away with metallic sounds in the reproduction of a record, the member 37 is preferably glued to the bridge 38 and the latter in turn is glued to the bottom 29. In order to secure the tone arm against unintentional removal, the pivot member 34 may be provided with a lug 39 adapted to project beneath a flange 40 of the coupling member 36. The flange 40 extends only partly about the coupling member 36 and forms an opening 40^a through which the lug 39 may be passed in one position to disconnect the tone arm 31 from the coupling member 36; the opening 41 is clearly shown in Fig. 3 and is so located that it is necessary, in order to permit disconnection of said tone arm from the coupling member, to bring the tone arm to a position other than any position assumed by it in the operation of the instrument. The tone arm 31 communicates by way of its open end 31^a with the interior of the casing 10 or, in other words, with the sound conduit provided thereby, it being understood that if desired, a cap or other device 41, preferably of a flexible material, may be provided on said tone arm 31 for closing the opening 33.

60 All of the parts of the phonograph which, in any way, contribute to the tonal quality of the instrument are constructed of wood and the fastening devices, such as screws, are maintained out of contact with said parts, for instance by passing through over-

size holes and by being insulated with leather or other suitable material to eliminate all objectionable and metallic sounds. Because of the resilient mounting of the tone arm and because of the relatively thin bottom 29 upon which it is supported, the instrument is rendered supersensitive with the result that the vibrations set up by the reproducer in co-operation with the record being played are sympathetically amplified and are communicated to the listener by way of the open end of the casing 10 as an efficient reproduction of the original represented by the record in question and with all metallic and other foreign noises entirely eliminated from said reproduction. The resonance of the instrument and its reproductive quality are further increased by bending the wood or certain parts thereof of which the element or elements constituting the sound conduit are constructed. While it is preferred from an ornamental standpoint to construct the phonograph, for instance in the form of a grand piano, it will be understood that this is not arbitrarily necessary and that any other divergent form may be used whereby the sound passing through the sound conduit, as exemplified by the casing 10, is amplified.

It will be noted that the motor 22 and the table 25 and all parts co-operating therewith are carried by the top member or cover 19, the latter being insulated from the casing while the screws 22^a whereby said motor is suspended are insulated from the cover 19; the motor and its correlated parts thus in no way interfere with the vibrations hereinbefore referred to and in no way contribute any vibrations of their own whereby the tonal quality of the phonograph might be detrimentally affected.

My improved phonograph is extremely simple in construction and reduces the number of parts to a minimum, and at the same time, provides an instrument whereby all of the natural qualities of the original from which the record is made are preserved in the reproduction and all metallic and other foreign sounds are eliminated therefrom.

Various changes in the specific form shown and described may be made within the scope of the claims without departing from the spirit of my invention.

I claim:

1. In a phonograph, the combination of a casing which itself constitutes the sound conduit for the passage of sound, said casing having an opening in its upper wall, a bottom of relatively thin wood constituting part of said casing and a tone arm extending from the exterior to the interior of said casing through said opening and having its inner end mounted upon said bottom and in communication with the interior of said casing.

2. In a phonograph, the combination of a casing which itself constitutes the sound conduit for the passage of sound, said casing having an opening in its upper wall, a bottom of relatively thin wood constituting part of said casing and curved inwardly both longitudinally and transversely and a tone arm extending from the exterior to the interior of said casing through said opening and having its inner end mounted upon said bottom and in communication with the interior of said casing.

3. In a phonograph, the combination of a casing which itself constitutes the sound conduit for the passage of sound, a tone arm extending freely from the exterior of said casing to the interior thereof and communicating therewith and means whereby the inner end of said tone arm is mounted upon the bottom of said casing.

4. A phonograph comprising a casing which itself constitutes a sound conduit, a bottom of relatively thin wood for said casing, a tone arm extending freely into said casing and communicating therewith, and means whereby said tone arm is resiliently mounted upon the bottom of said casing.

5. A phonograph comprising a casing which itself constitutes a sound conduit, a

bottom of relatively thin material for said casing, a bridge located upon said bottom at approximately the central point thereof, a member having its one end secured to said bridge and extending therefrom in spaced relation to said bottom to provide a resilient support, and a tone arm extending freely into said casing and communicating therewith, said tone arm being connected with and supported by said member.

6. A phonograph comprising a casing which itself constitutes a sound conduit, a relatively thin flexible bottom for said casing, a resilient member mounted upon said bottom and connected therewith approximately at its central point, a coupling member carried by said member, a tone arm extending freely into said casing and mounted upon said coupling member so as to swing relatively thereto and means whereby said tone arm is connected with said coupling member without interference with the swinging movements of said tone arm.

In testimony whereof I have hereunto set my hand.

HERMAN ROTHKIRCH.

Witness:

JOHN F. KLEIN.
